ADJUSTABLE GAUGE

Filed Nov. 1, 1927

UNITED STATES PATENT OFFICE

CHARLES E. POST, OF LOS ANGELES, CALIFORNIA

ADJUSTABLE GAUGE

Application filed November 1, 1927. Serial No. 230,278.

This invention relates to the building art, and is more particularly concerned with an adjustable gauge for obtaining relatively angled measurements such as inside measurements, and including angles, such for example, as are necessary in stair work, shelving and other forms of work requiring inside measurements and angles for cutting to fit.

An object of the invention is the provision of a durable gauge of simple construction adjustable to a relatively wide range of work, including inside measurements involving variably angled sides. These features as well as other structural features and advantages are more fully defined in the following detailed specification, when read in connection with the accompanying drawings forming part thereof, and in which:

Figure 1 is a plan view of the gauge unextended and with the side gauging arms at the perpendicular, the extension of the longitudinal gauge bars and the angled adjustment of the side angle bars or arms being shown in dotted lines.

Figure 2 is a perspective detail of the gauge shown in full lines in Figure 1.

Figure 3 is a vertical section on an enlarged scale through the adjusting clamp taken on the line 3—3 of Figure 1.

Figure 4 is a sectional view on an enlarged scale taken on the line 4—4 of Figure 1.

Figure 5 is a sectional view on a similarly enlarged scale through a guide yoke taken on the line 5—5 of Figure 1.

In carrying out the invention, provision is made for a sectional bar, which may be termed a length bar, comprising overlapping bar sections 1 and 2, preferably of flat steel, connected together for longitudinal extension and contraction. To this end, the inner bar 1, as viewed in Figure 2, is provided at one end with a yoke 3 to which it may be affixed by suitable means, such as a screw 4. The yoke 3 embraces also the outer bar section 2, which at its opposite end is provided with a similar yoke 10, embracing also the inner bar 1 in a manner later to be described. The end of the inner bar 1, opposite the yoke 3, extends through and beyond the yoke 10, and is provided with an angularly offset end 5 to

which one end of a side angle arm or bar 6 is pivotally secured. Preferably, the side angle arm 6 is provided adjacent to its end with a threaded stud 7, which extends freely through a pivot hole formed in the offset end 5, and is engaged by a clamping arm 9, having a threaded bore therein into which the projecting end of the stud 7 threads. A suitable washer 8 is interposed between the face of the offset and the clamping arm 9. Turning the clamping arm obviously draws the face of the bar 6 against the end 5 and clamps it thereto.

The yokes 3 and 10, as previously stated, join the sections 1 and 2 of the extensible length bar and guide them in parallel relation. The yoke 10 carries means, in the form of a threaded stud 11 with a suitable operating head, by means of which the bar sections 1 and 2 may be clamped together in their longitudinally adjusted positions. The stud 11 is threaded through aligned apertures in the yoke 10 and outer bar 2 to impinge against the inner bar 1 and to clamp it against the opposite side of the enclosing yoke.

The opposite end of the outer bar section 2 is provided, similarly to the inner section 1, with an angularly inclined end 12, upon which the end of a complementary side angle bar 13 is pivotally mounted by means of its stud 14 projecting freely through a pivot aperture in the end 12, and engaged at its outer projecting end by a similar clamping arm 15, a washer 16 being interposed between the clamping arm and the adjacent face of the end 12.

The outwardly and upwardly inclined ends 5 and 12 of the length bar are of decided advantage in enabling the side angle arms 6 and 13 to fit within and engage with their edges the inner faces of work to be gauged, where the angles of these faces to the length bar is other than right angular. The gauge, being formed of flat steel bars, is practically indestructible, and will withstand considerable abuse. The side arms, when the gauge is not in use, may be folded down to lie over and parallel with the length bar, so that when the latter is shortened to its minimum length, and the side arms collapsed thereover, the

gauge occupies a minimum of space commensurate with its range of adjustment. Obviously, this range is substantial since the extended length of the bar sections 1 and 2 is practically double that of their collapsed length, and the side arms 6 and 13 being of a length adequate to cover a substantial area not interfering with the collapsing of these arms over the length bar. The arms 5 and 12 at the opposite ends of the length bar which form permanent extensions thereof are inclined outwardly in divergent relation to said bar and are advantageous when their respective side angle bars 6 and 13 are to be used to measure, for example, for the side angularity of the sides of a shelf or stair tread having sides divergent outwardly toward their inner longitudinal edges from a longitudinal outer edge of less length. The inclined arms or ends 5 and 12 of the length bar, under these conditions, can by adjustment of the vertical length of the length bar sections 1-2, be inserted inwardly beyond the outer longitudinal edge and the side angle arms 6 and 13 can be adjusted to contact the sides of the opening and gauge the side angularity of the stair tread or shelf. Were these arms 6 and 13 pivoted to the arms of the length bar 1-2 in its linear dimension, this would not be possible.

While the form of the invention illustrated and described herein is a preferable one, it is intended as illustrative of the invention rather than restrictive, and it is contemplated that various structural changes and adaptations may be made in consonance with the spirit of the invention and the scope of the appended claim.

What I claim and desire to secure by Letters Patent is:

A gauge comprising a length bar composed of overlapping rectilinear sections yoked together for relative longitudinal extension and contraction and provided with means for fixing them in longitudinally adjusted positions, said sections at their outer extremities having rigid extensions inclining outwardly and upwardly in divergent relation relatively to one another, side angle bars, threaded studs pivotally connecting one end of the side bars to the outer ends of said divergent extensions, said bars being adjustable on said pivots to define with their edges side angular relations to said length bar, and clamping arms threaded on said studs for clamping said side angle bars to said extensions in such angularly adjusted relations.
